UNITED STATES PATENT OFFICE.

JACK KATZ, OF NEW YORK, N. Y.

DESIGN FOR A CLOCK CASE.

Application filed July 21, 1927. Serial No. 22,834. Term of patent $3\frac{1}{2}$ years.

To all whom it may concern:

Be it known that I, JACK KATZ, a citizen of the United States, and residing at New York, in the county of New York and State of New York, have invented a new, original, and ornamental Design for a Clock Case, of which the following is a specification, reference being had to the accompanying drawings, forming part hereof.

The figure is a perspective view.

I claim:

The ornamental design for a clock case, as shown.

JACK KATZ.
